CLAIM

The ornamental design for a manual coffee grinder, as shown and described.

DESCRIPTION

FIG. 1 is a front, right and top perspective view of a manual coffee grinder, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is another front, right and top perspective view of the manual coffee grinder in another state.

FIG. 11 is a front, right and top perspective view of a second embodiment of a manual coffee grinder.

FIG. 12 is a rear, left and bottom perspective view of the second embodiment of the manual coffee grinder of FIG. 11.

FIG. 13 is a front elevation view of the second embodiment of the manual coffee grinder of FIG. 11.

FIG. 14 is a rear elevation view of the second embodiment of the manual coffee grinder of FIG. 11.

FIG. 15 is a left side elevation view of the second embodiment of the manual coffee grinder of FIG. 11.

FIG. 16 is a right side elevation view of the second embodiment of the manual coffee grinder of FIG. 11.

FIG. 17 is a top plan elevation view of the second embodiment of the manual coffee grinder of FIG. 11.

FIG. 18 is a bottom plan elevation view of the second embodiment of the manual coffee grinder of FIG. 11.

FIG. 19 is an enlarged view of detail 19 in FIG. 11; and,

FIG. 20 is another front, right and top perspective view of the manual coffee grinder of FIG. 11 in another state.

The broken lines depict portions of the manual coffee grinder that form no part of the claimed design. The dot-dash

(Continued)

broken lines in FIGS. 1, 9, 11, and 19 depict the boundaries of the enlargements that form no part of the claimed design.

1 Claim, 20 Drawing Sheets
